UNITED STATES PATENT OFFICE.

GEORGE E. WHITNEY, OF BRIDGEPORT, CONNECTICUT.

PRESS.

1,394,458.

Specification of Letters Patent. Patented Oct. 18, 1921.

Application filed January 16, 1919. Serial No. 271,384.

To all whom it may concern:

Be it known that I, GEORGE E. WHITNEY, a citizen of the United States, and a resident of Bridgeport, county of Fairfield, and 5 State of Connecticut, have invented an Improvement in Presses, of which the following description, in connection with the accompanying drawings, is a specification, like characters on the drawings representing like 10 parts.

This invention relates to presses, and more particularly to presses intended for reducing compressible material to a highly compressed state.

15 The invention will be best understood by reference to the following description when taken in connection with the accompanying illustration of one specific embodiment thereof, while its scope will be more particularly 20 pointed out in the appended claims.

In the drawings:

Figure 1 is a central longitudinal section showing the materials-receiving end of a press to which one form of the invention is 25 applied;

Fig. 2 is a similar cross-sectional elevation of the opposite or discharge end of the press;

Fig. 3 is a cross-sectional elevation taken 30 on the line 3—3 in Fig. 2 looking in the direction of the arrow;

Fig. 4 is a similar cross-sectional elevation taken on the line 4—4 in Fig. 1 looking in the direction of the arrow; and

35 Fig. 5 is a cross-sectional elevation taken through the journal of the pusher arm showing the steam heating connections therefor.

For the purposes of illustration I have shown one embodiment of the invention in 40 a simple, well known type of press, the general arrangement of which is indicated more or less conventionally, but which is sufficient to illustrate the use and adaptation of my invention. The specific form of press is 45 shown for illustrative purposes only, my invention not being limited in its application to any particular type of press or to any particular kind of material to be compressed. The press may be either a baling press where 50 the compressed material is bound into bales while passing through the same, or the material may be compressed and subdivided after leaving the press, or the press may be utilized to recompress previously baled ma- 55 terial.

In the illustrated form of press, the ma-

terials to be compressed are entered by batches or charges into a materials-receiving chamber 10 through any suitable opening, such as the entrance opening 11 which is 60 surmounted by the hopper 12. In the receiving chamber the materials are acted upon by a suitable compressing element which is typified by the reciprocating compressing plunger 13. Reciprocatory movement is 65 imparted to the latter by any suitable means, as by the connecting rod 14 and crank 15, the latter rotated by the crank shaft 16 from any suitable source of power, so that the materials are forced into a compression 70 space or chamber 17. This is herein in the form of a box-like inclosure having a rectangular cross section serving as a prolongation of the receiving chamber 10 and has a discharge end 18 through which the compressed material advances step by step with 75 each reciprocation of the compressing plunger.

The compression of the material is effected by the plunger 13 against the resistance offered to the passage of the already compressed material in contact with retarding walls or surfaces, the density of compression depending upon the amount of friction to be overcome by the plunger in moving 85 the material along a discharge passage or runway.

To provide the desired frictional resistance to the compressed material, the discharge passage is extended beyond the discharge end 90 18 of the compression chamber in the form of a discharge runway comprising the upper and lower plates 20 and 21 respectively, together with the side walls presented by the angle irons 22 and 23 respectively, secured to 95 the upper and lower plates. These angle irons present side walls which guide the compressed material and confine it laterally.

In the illustrated form of the invention the lower plate 21 of the runway with its 100 side plates 23 is fixed immovably upon the transverse pieces 30 forming a part of the bed 31 of the machine, but the upper plate 20 with its side plates 22 is so supported upon the stationary bed as to be susceptible 105 of movement.

To support the upper plate longitudinal I-beams 32 (herein three in number) are provided extending directly over the plate. At one end the I-beams rest upon upright supports 33 mounted on the frame of the compression chamber, and at the opposite end 110

are secured to a cross-beam 34. Cross pieces 35 are provided at intervals resting upon the I-beams and secured to the stationary frame by means of tie rods 36, the lower ends of which are fastened to the underlying transverse bed pieces 30.

At separated points on the I-beams there are provided cross bars 37 with depending hangers 38 to which are jointed links 39, the lower ends of the links being jointed to members 40 secured to similar cross pieces 41 which are mounted on I-beams 42 extending longitudinally and secured to the top of the friction-producing or frictional retarding plate 20.

Herein there are three sets of I-beams 32 and 42 and three sets of hangers at each supported point of the retarding plate, but any suitable number may be used and any desired number of such sets may be employed, depending on the length of the retarding plate and other conditions of mechanical detail.

The end of the retarding plate 20 nearer the compressing chamber is prevented from moving beyond a certain limit in the direction of the hopper by an angle iron 43. Under certain conditions, however, it may move longitudinally with the compressed material, or in the direction indicated by the arrow in Fig. 2, the links swinging about their pivotal supports to permit such movement. Such movement, however, is under suitable control, and herein under the control of yielding means which normally resist such movement but yield and permit it when the frictional contact of the compressed material with the upper plate 20 and side walls 22 exceeds a predetermined desired amount.

While yielding means of various kinds may be employed to yieldably resist the movement of the retarding plate 20, herein each link has a longitudinally extending arm 50, the end of which has an adjustable set screw 51 engaging a cap or abutment 52 resting upon the top of a compression spring 53, the lower end of which rests upon an abutment 54 carried by the underlying I-beam 42. Any movement of the plate in the direction of the arrow (Fig. 2) tends to swing the links 39 and depress the arms 50 acting to compress the springs 53.

Since a substantial amount of the friction in the discharge passage, and herein substantially half, is produced by contact between the compressed material and the movable plate or retarding wall, the forces tending to move the plate longitudinally will depend on the frictional resistance in the runway and will substantially measure the force under which compression is effected in the compression chamber. By suitably adjusting the springs, therefore, this movement may be permitted to take place when a certain fric-

tional resistance or a certain compression resistance is attained. The aggregate force exerted by all the springs may thus be sufficient to balance one-half or any other desired part of the compression effort of the plunger. The initial compression of the springs may be adjusted by adjusting the set screws 51 and the press may thereby be set to any desired pressure or degree of compression, and this pressure may be changed from time to time as required.

In the illustrated form of the invention the links are so arranged that the longitudinal movement of the plate with the material also lifts the end of the plate adjacent the discharge end of the runway, thereby tilting it upward and expanding or enlarging the discharge passage by an increasing amount toward the discharge end. For this purpose the links are connected to the upper and lower I-beams respectively at points which slightly offset the upper and lower connections respectively as the discharge end is approached, and give an increasing angular inclination to the links toward the discharge end, so that the longitudinal movement of the plate 20 in the direction of the arrow effects also a lifting movement of the plate near its discharge end. This lifting movement, as well as the longitudinal movement may be made of any desired extent by suitably proportioning the parts, but is preferably, though not necessarily, considerably less than the longitudinal movement, so that the enlargement of the discharge opening and the relief afforded the material is very gradual as the plate first starts to move. Preferably also, though not necessarily, the links are given such a relation that this lifting movement is at a maximum at the discharge end of the runway, and no appreciable lifting movement takes place at the opposite end thereof.

Figs. 1 and 2 show the plate 20 and its connections in the position which they normally occupy after the press has been started into operation and as the compressed material is passing through the runway under the designed frictional retardation and producing the desired compression resistance at the compression chamber. If the conditions become altered at any time by an increase in the friction and any tendency to stoppage or obstruction, thereby increasing the compression resistance at the compression chamber, the springs 53 yield when this definite pressure is exceeded and the upper portion of the runway, including the top plate 20 and the side plates 22, yield and move longitudinally in the direction of travel of the material, while the upper portion of the runway as a whole starts to tip slightly at its outer end.

Conversely, if the frictional resistance drops below the required point, the plate 20,

under the action of the springs 53, tends to move in a direction opposite to the direction of the arrow in Fig. 2, tilting or tipping down the discharge end of the plate and contracting the discharge passage, the point of greatest contraction being near the discharge end thereof. This increases the frictional resistance and again builds up the compression to the required amount, whereupon the 10 plate will again move to or toward its mid position, the springs yielding to permit such movement when the desired frictional resistance is attained.

This automatic governing action of the 15 discharge runway may also be utilized to start the press into operation and oppose a frictional resistance to the passage of the compressed material until the required pressure has been produced. To this end, the 20 links 39 are preferably so arranged that when there is no material in the runway the discharge end of the plate is permitted to drop to a position somewhat below the horizontal, so that it provides a tapered runway 25 contracting more or less at its discharge end.

As illustrative of elevated and depressed positions to which the end of the movable plate may move in its automatic governing action on the frictional resistance, I have 30 shown two such positions by dotted lines at x and y respectively, and have indicated by the tapered dotted lines, the corresponding positions assumed by the lower surface of the retarding plate. It will be understood, however, that the lift and depression of the plate are shown by these dotted lines on a somewhat exaggerated scale.

With the press empty, the material is entered into the receiving chamber 10 and 40 moved into the compression chamber 17 by the successive movements of the plunger 13. As the material thus passes into the discharge passage, its frictional resistance gradually builds up a compression resistance 45 in the compression chamber and, in turn, increases the frictional resistance in the runway. When the material approaches the contracted end of the runway, this resistance increases and the further passage of the material is prevented until the compression resistance has been built up to a point sufficient to move the plate to a substantially horizontal position, shown in full lines. In 50 this position it acts as an automatic governing 55 nor regulating the frictional retardation of the compressed material, tending to expand or contract the end of the discharge runway and relieve or increase the frictional resistance, according as the resistance in the compression 60 chamber rises above or drops below the predetermined amount.

Under ordinary conditions only a relatively slight longitudinal movement and a relatively slight lifting movement of the 65 retarding plate is needed to regulate the

frictional resistance. Under some circumstances, however, a more pronounced or abnormal taper may be desirable. Thus in starting up the press or in using some material having an unusually low friction, or of such a nature as to produce a low frictional resistance, a greater depression of the plate may be required than is provided by the links 39. For this purpose I have provided means whereby the entire supporting frame 70 which carries the links may be adjustably depressed (or raised if required) more or less near the discharge end of the press, thus giving the runway an extreme taper as compared with the normal working taper. To 75 this end, the I-beams 32 are fulcrumed at 60 near the hopper end of the press where they are secured to the support 33. At the opposite end they are made vertically adjustable by the vertical adjustment of the cross-bar 34. The latter is clamped to the upright rods 61 and by adjusting the clamping nuts 62 and 63 the supporting frame at the discharge end of the press may be lowered (or raised) more or less, the intermediate tie 80 rods being correspondingly adjusted. By this means the runway may be given an initial abnormal taper which, however, is subjected to automatic variation within the limits permitted by the action of the links. 85

Any suitable means may be employed in the compression chamber for holding the material entered therein by the plunger, such as the spring-pressed dogs 65 similar to the dogs shown in my prior Patent No. 1,217,893. 90

Where compressible material is handled which becomes sticky when compressed, it may be desirable to heat the surfaces along which the material passes, thereby to soften 105 the surface of the body of material and prevent its sticking, and for this purpose I have shown the compression chamber for a suitable portion of its length surrounded by a steam jacket 70 connected with suitable admission and exit steam-pipe connections 71 and 72 respectively. As the compression plunger 13 retracts, a pusher 75 is caused to enter into the hopper and depress the next batch of material into the receiving chamber 110 in front of the plunger preparatory to its being advanced into the compression chamber on the next stroke of the plunger. The pusher is carried by two arms 80 (Figs. 1 and 5) projecting from an oscillating frame 115 mounted to oscillate in the upright frame members 81, each arm having a depending projection 82 which is connected by a link 83 with the plunger 13. The connections are such that as the plunger retracts the 120 pusher executes a movement down into and through the hopper, and as the plunger advances the pusher retracts from the receiving chamber and the hopper. 125

Herein I have also shown means for heat- 130

ing the pusher so that where the material is of a nature that it might soften under heat as the pusher crowds the material down into the receiving chamber, it not only assists in 5 softening the material, but any tendency of the material to stick to the pusher is prevented. Preferably means are provided such that any desired temperature may be maintained, as, for example, the necessary 10 temperature to prevent the sticking of the material which is being fed to the receiving chamber.

Herein, as illustrative of such means, I have shown a steam pipe connection 84 controlled by a suitable valve 85 and connecting through one of the hollow trunnions of the oscillating frame, with passages 86 extending up through one of the arms 80 and entering the hollow pusher head 75. Circulation of the steam through the pusher head is maintained by the exit passage 87 extending through the remaining arm 80 and connected in a similar manner to the pipe 88.

Claims.

25. 1. In a press, the combination with a reciprocating plunger acting in a suitable compressing chamber, of a discharge passage providing frictional resistance for the compressed material passing from the compression chamber, means for regulating the frictional resistance, comprising a frictional retarding plate constituting a wall for said discharge passage, means comprising a series of links for holding said wall to permit the latter to move longitudinally in the direction of travel of the compressed material, successive links being arranged in different angular relation to cause said longitudinal movement to tip or open said wall toward 40 the discharge end, thereby giving an enlarged cross-sectional area to the discharge passage at its discharge end but diminishing toward the opposite end, and one or more compression springs adapted to oppose the 45 movement of said wall and yieldable only when a given compression resistance is reached.

50. 2. In a press, the combination with compressing means, of a compression chamber, a materials-receiving chamber, a pusher for entering the material into the receiving chamber, and means for heating the pusher.

3. In a press, the combination with a com-

pressing member, of a pusher for pushing the material in front of the same, and means 55 for heating the pusher.

4. In a press, the combination with a compression plunger, a compression chamber, means for pushing the material in front of the plunger, means for heating the pusher, 60 and means for heating the compression chamber.

5. A press comprising, in combination, a reciprocating plunger acting in a suitable compressing chamber, a discharge passage 65 providing frictional resistance for the compressed material passing from the compressing chamber, means for regulating the frictional resistance, comprising a frictional retarding plate constituting a wall for said 70 discharge passage, means comprising a series of links for holding said wall to permit the latter to move longitudinally in the direction of travel of the compressed material, and yielding pressure-determining 75 means adapted to oppose the movement of said wall and yieldable only when a given compression resistance is reached.

6. A press comprising, in combination, a reciprocating plunger acting in a suitable 80 compressing chamber, a discharge passage providing frictional resistance for the compressed material passing from the compressing chamber, means for regulating the frictional resistance, comprising a frictional retarding plate constituting a wall for said 85 discharge passage, means including a series of bell cranks for holding said wall to permit the latter to move longitudinally in the direction of travel of the compressed material, said bell cranks each pivotally connected at the end of one arm to said wall, and each connected to said wall by yielding compression means at the end of the other arm, said bell cranks intermediately fulcrumed to an abutment, and said retarding plate and bell cranks organized and operating to permit longitudinal movement of said 95 plate when a predetermined compression resistance is reached and providing for enlargement of said discharge passage, dependent upon the extent of longitudinal movement of said plate.

In testimony whereof, I have signed my name to this specification.

GEORGE E. WHITNEY.
